UNITED STATES PATENT OFFICE.

OSIAS O. KRUH, OF SCHENECTADY, NEW YORK, ASSIGNOR TO GENERAL ELECTRIC COMPANY,
A CORPORATION OF NEW YORK.

VAPOR ELECTRIC APPARATUS.

No. 883,030.

Specification of Letters Patent. Patented March 24, 1908

Application filed September 15, 1905, Serial No. 278,554. Renewed January 31, 1908. Serial No. 413,612.

To all whom it may concern:

Be it known that I, OSIAS O. KRUH, a subject of the Emperor of Austria-Hungary, residing at Schenectady, in the county of 5 Schenectady and State of New York, have invented certain new and useful Improvements in Vapor Electric Apparatus, of which the following is a specification.

My present invention relates to vapor electric devices and more particularly to that type having a highly exhausted envelop provided with a plurality of positive electrodes or anodes, such, for example as the rectifiers or lamps used on single-phase or 15 multiphase alternating-current circuits. In devices of this character, there is a tendency found to exist in practice for arcs to form more or less momentarily between main anodes. The causes which contribute to the 20 production of such arcs are various and it is one of the objects of my invention to overcome as far as possible any tendency which may exist for such arcing to take place.

The various features of novelty which 25 characterize my invention are pointed out with particularity in the appended claims. The invention itself, however, will be better understood by reference to the following description taken in connection with the accompanying drawings, which represent by way of illustration one of the various embodiments which my invention may assume in practice.

While my invention is applicable to vapor 35 electric devices adapted to alternating-current circuits of any number of phases, I have in the drawings represented a device arranged more especially for use with single-phase alternating current. The particular 40 device chosen for illustration is a rectifier for single-phase alternating-current in which the rectifier tube itself is of a special construction particularly fitted to prevent the arcing between the anodes. I may here say that by 45 the word "anode" I mean an electrode which serves as the positive terminus of an electric arc in which the current flows unidirectionally.

The rectified tube shown in the drawings is so fashioned as to direct the arc blast or discharge of luminous vapor from the cathode 50

as to shoot by or past the anodes. The anodes are thus in a great measure protected from the peculiar rays or other emanations from the cathode which I have found are apt to cause arcing to take place between the 55 anodes.

Referring to the drawings, the rectifier tube has a central member of any desired shape, in this case more or less globular, as indicated at 1. Arms or pockets 2 3 extend laterally from this globular portion and are bent upwardly at a slight angle as indicated. These pockets form receptacles for the main 60 anodes 4 and 5 of the rectifier. These anodes may be made of artificial graphite or other suitable material and are connected respectively to leading-in conductors 6 and 7. These leading-in conductors where they project into the pockets or chambers 2 and 3 are protected by glass sleeves 8 and 9 which surround the leading-in conductors and flare 70 over the ends of the anodes as indicated.

From the lower portion of the bulb 1 a tubular member 10 extends, the lower end of which is closed, and carries a body of mercury 11, constituting the cathode or negative electrode. A leading-in conductor 12 makes electrical connection in the usual manner with this cathode. Adjacent to the cathode there is arranged a laterally and downwardly projecting chamber or pocket 13 carrying a body of mercury 14 constituting an auxiliary or starting electrode. Electrical connection with this electrode is made as in the case of the other electrodes by means of a 85 leading-in conductor 15.

From the upper end of the globular portion 1 of the rectifier tube there extends a relatively large tubular member 16 which constitutes a condensing chamber for the surplus mercury vapor produced during normal operation of the rectifier. Into the mouth of this condensing chamber I cause the discharge or blast from the cathode to be directed by means of a discharge-directing tube 90 17. This tube fits down into the tubular portion 10 and may conveniently rest upon a shoulder or some other suitable contraction 95 18 formed in the tube 10. The lower edge of the tube 17 may have one or more scallops or 100

openings therein so as to permit any mercury which may fall down between the tube 17 and the upper portion of the tube 10 to pass through and thereby be returned to the cathode 11.

It is necessary that no drops or particles of mercury be allowed to drop against either of the anodes 4 and 5 during normal operation, inasmuch as this would be apt to cause arcing between the anodes. Therefore, to prevent the mercury globules as they flow back from the condensing chamber 16, from falling into the space outside of the tube 17 where they might by impact against the walls of the apparatus splash against the anodes, I form the condensing chamber with a tapered or hopper-shaped contraction 19 so as to direct the falling particles of mercury into the mouth of the tube 17. In furtherance, also, of this end, the mouth of the tube 17 may itself be flared somewhat as at 20 so as the more surely to intercept falling drops or globules of mercury.

It will be noticed that the tube 17 extends past the mouths of the pockets or chambers 2 and 3 and thereby shields the anodes in these chambers from all those emanations from the cathode except those which serve as the current-carrying medium between the cathode and the respective anodes.

In normal operation, there is observed not only the arc streams which pass up through the tube or chimney 17 and then bend down and pass to the anodes, but also a luminous blast or stream which passes from the chimney 17 through the contraction 19 into the condenser chamber where it is dispersed. There are certain emanations from the cathode stream from which it is desirable that the anodes should be protected, which emanations may be something in the nature of ultraviolet rays. Though I am not certain as to the exact nature of these rays, it is certain that there is some kind of a radiation or emanation which if the anodes should be directly exposed to it may cause arcing to take place between them. This particular radiation is screened off from the anodes by making the tube 17 of a material to which the radiation is more or less impervious. Thus, the tube 17 may be made of glass, metal or other incombustible material but should not be made for example of fused quartz which appears to be more or less transparent to rays of the character mentioned.

The rectifier which I have described may be connected in circuit in a manner now well understood in the art. I have indicated these connections diagrammatically in the drawings.

The supply mains are shown at 21 and 22 and are connected by leads to the anodes 4

and 5 as indicated. The coils 23 and 24 of a reactance device are connected across these mains and the junction 25 between these coils is connected to one main 26 of the consumption circuit fed by the rectifier. The other main 27 of the consumption circuit goes to the cathode 11 as shown. The starting anode 14 is connected, for purposes of starting, through a resistance 28 to one of the supply mains and serves, when the rectifier is shaken so as to bring the anodes of mercury 14 and 11 momentarily together, to constitute the anode of an auxiliary arc. This auxiliary arc serves in a well understood manner to set the apparatus in operation, whereupon the auxiliary anode may be cut out of circuit.

It is obvious from the foregoing description of my improved rectifier and of the functions of its various parts, that the rectifier may be greatly altered in shape and construction without departing from the spirit of my invention, for which reason I, of course, do not wish to be limited to the details shown and described.

The devices shown in this application are covered broadly by the claims in my application Serial No. 194,520 filed February 20, 1904, which is now involved in interferences. The present case is limited to the improvements on the invention of said former application which are herein described and claimed, and the claims herein are therefore not to be construed as covering anything disclosed in my said prior application.

What I claim as new and desire to secure by Letters Patent of the United States, is:

1. In a vapor electric apparatus, an exhausted envelop having a plurality of anodes each located in a separate chamber, a cathode, and a tube confining the discharge from the cathode and extending past the openings into the chambers containing the anodes.
2. A vapor electric apparatus comprising an exhausted envelop having a plurality of anodes and a cathode, and a tubular member confining the discharge from the cathode.
3. In a vapor electric apparatus, an exhausted receptacle having a cathode and a plurality of anodes therein, a condensing chamber having a contracted opening, and means for directing the discharge or blast from the cathode towards said opening.

4. In a vapor electric apparatus, an exhausted envelop or receptacle having a cathode and a plurality of anodes located therein, and a tube for carrying the blast or discharge from the cathode past the anodes.

5. In a vapor electric apparatus, the combination of an envelop or receptacle having a plurality of projecting arms or chambers, electrodes in said arms or chambers, a vaporizable electrode located also in said envelop,

and means for causing the arc or discharge from said vaporizable electrode to be projected past the openings into said arms or chambers.

6. In a vapor electric apparatus, an envelop or receptacle having a plurality of chambers, anodes located respectively in said chambers, a coöperating cathode, and an arc-

confining tube or member subtending the openings into said chambers.

In witness whereof, I have hereunto set my hand this 14th day of September, 1905.

OSIAS O. KRUH.
